UNITED STATES PATENT OFFICE.

ARTHUR TREVOR DAWSON, OF WESTMINSTER, LONDON, AND JAMES HORNE, OF BARROW-IN-FURNESS, ENGLAND, ASSIGNEES TO VICKERS LIMITED, OF WESTMINSTER, ENGLAND.

CONTROL OF THE BREECH-ACTUATING MECHANISM AND LOADING APPARATUS OF HEAVY GUNS.

1,094,129.

Specification of Letters Patent. Patented Apr. 21, 1914.

Application filed September 30, 1911. Serial No. 652,192.

To all whom it may concern:

Be it known that we, ARTHUR TREVOR DAWSON, knight, and JAMES HORNE, both subjects of the King of Great Britain, residing, respectively, at Vickers House, Works, Barrow-in-Furness, in the county of London, England, and Naval Construction Works, Barrow-in-Furness, in the county of Lancaster, England, have invented certain new and useful Improvements in or Relating to the Control of the Breech-Actuating Mechanism and Loading Apparatus of Heavy Guns, of which the following is a specification.

15 This invention relates to the control of the breech actuating mechanism and loading apparatus of heavy guns of the kind in which the operating motors are controlled by valves carried by a part of the mounting that does not move with the gun in elevation.

According to the present invention one or more of the motors on the slide frame or loading arm are controlled by a valve 25 or valves also carried by the slide frame or loading arm, the movements of the said valves being under the influence of hand actuated valves on the gun platform. By these means the motor or 30 motors on the slide frame or loading arm can be controlled independently of the hand actuated valve or valves by the automatic means hereinafter described.

In order that the said invention may be 35 clearly understood and readily carried into effect we will describe the same more fully with reference to the accompanying drawings in which:

40 Figures 1 and 1^a together represent a dia- grammatic side elevation showing our im- provements. Fig. 2 is an enlarged sectional elevation of the breech actuating motor and its control valve, and Figs. 3 and 4 are enlarged sectional elevations of the control 45 hand levers and valves for the breech mechanism and for the powder doors respectively.

A is the gun, A' the slide frame, A² the loading arm, A³ the rammer carried there- 50 by, A⁴ the rammer control hand lever and a² the valve connected thereto.

B is the breech actuating motor, B' the

control valve for the same, B² the control hand lever, and b' the valve connected thereto.

55

C is the loading cage, C' the press for the same, C² the control valve, C³ the control hand lever for the said press, c³ the control hand lever for the powder doors of the said cage and c² the valve connected to the said 60 lever c³.

D is the hand wheel by which the breech can be manually opened and closed when desired.

E is the hand lever and E' the valve for 65 controlling the running out of the gun.

F is the pressure fluid main and G the ex- haust main.

The control valve B' is in the form of a differential ram, and the port b^x is connect- 70 ed by means of a pipe b with the valve b' of the lever B² mounted on the gun plat- form. The movements of the said hand lever displace the valve b' to admit pres- 75 sure fluid through the pipe b to the main control valve B' of the breech actuating motor or to place the same to exhaust, the direction in which the said hand lever is shifted, determining the direction in which the valve B' will move (owing to the fact 80 that it is in the form of a differential ram as aforesaid and is under constant pressure fluid from the pipe b⁰) and consequently the direction in which the motor B will work. The motor is connected to a screwed 85 shaft B³ provided with a nut b² which is adapted to coöperate with stops b³, b³ on the stem of the valve B' to automatically move the said valve and cause the motor B to stop at the completion of the opening and 90 closing of the breech.

The rammer A³, which is shown by way of example as of the flexible or chain type, is under the influence of an hydraulic motor (not shown) controlled by a valve a carried by the loading arm. The casing of the said valve is connected by a pipe a' with the hand control valve a² of the hand lever A⁴ of the rammer controlling mechanism, the cut off valve a³ carried by the gun slide be- 100 ing adapted to coöperate with the rammer A³ and being connected with the reversing cylinder a⁴ on the gun platform by a pipe a⁵. In order to prevent the rammer from leav-

ing the withdrawn position until the gun loading cage C is in alinement with the bore of the gun, and for causing the rammer to automatically perform its first ramming stroke, a spring bolt a^x is adapted to co-operate with the stem of the control valve a to lock it in the position to retain the rammer in the withdrawn position. A stop c on the gun loading cage C co-operates with the said spring bolt a^x and withdraws it from engagement with the stem of the control valve a as the cage reaches its loading position, whereupon, the hand lever A^4 having been previously placed to the "ram" position, the valve a will move into the position to cause the rammer to ram the projectile into the gun. The usual locking bolt A^x is provided on the loading arm for retaining the loading cage C in position until the rammer has been fully withdrawn.

The means for operating the powder doors of the gun loading cage comprise an hydraulic press c^x mounted on the loading arm and co-operating with a lever or crank c' on the powder doors. The said hydraulic press c^x communicates through a pipe c^4 with the control valve c^2 the movements of which by the hand lever c^8 admits pressure fluid to the press c^x or places the same to exhaust as required, the constant pressure fluid supplied by the pipe c^5 causing the press to move when the pipe c^4 is placed to exhaust.

The control valve C^2 of the gun loading cage is operated by the hand lever C^3 on the gun platform in the usual manner. We combine with the valve C^2 an intercepting valve C^x connected by a pipe c^{xx} with a valve (not shown) operated by a part of the breech mechanism, the arrangement being such that the cage C is prevented from ascending until the breech has been completely opened and the gun fully run out.

What we claim and desire to secure by Letters Patent of the United States is:—

1. In gun breech actuating and loading apparatus, the combination with the slide frame, the breech actuating motor carried thereby, and the motor control hand lever mounted on a part of the mounting that does not move in elevation, of a control valve carried by the slide frame, and pressure fluid means for actuating said valve from the aforesaid hand lever.

2. In gun breech actuating and loading apparatus, the combination with the slide frame, the breech actuating motor carried thereby and the motor control hand lever mounted on a part of the mounting that does not move in elevation, of a control

valve carried by the slide frame and hydraulic means for actuating said valve from the aforesaid hand lever.

3. In gun breech actuating and loading apparatus, the combination with the slide frame, the breech actuating motor carried thereby, and the motor control hand lever mounted on a part of the mounting that does not move in elevation, of a control valve carried by the slide frame, a valve operated by the said hand lever, and means for connecting said valve to the control valve on the slide frame.

4. In gun breech actuating and loading apparatus, the combination with the slide frame, the breech actuating motor carried thereby, and the motor control hand lever mounted on a part of the mounting that does not move in elevation, of a control valve carried by the slide frame, a valve operated by the said hand lever, and hydraulic means for connecting said valve to the control valve on the slide frame.

5. In gun breech actuating and loading apparatus, the combination with the slide frame, the breech actuating motor carried thereby and the motor control hand lever mounted on a part of the mounting that does not move in elevation, of a differential control valve carried by the slide frame, a pipe supplying constant pressure fluid to said differential valve, a valve operated by said hand lever and a pipe connecting said valve with the differential valve on the slide frame.

6. In gun breech actuating and loading apparatus, the combination with the gun platform, the slide frame, the breech actuating motor carried thereby and the motor control hand lever mounted on the gun platform, of a differential control valve carried by the slide frame, a pipe supplying constant pressure fluid to said valve, a valve mounted on the gun platform and operated by the said control hand lever, and a pipe connecting said valve with the differential valve on the slide frame.

In testimony whereof we affix our signatures in presence of two witnesses.
